His Attorney.

UNITED STATES PATENT OFFICE

EMILE C. GUEDON, OF SCHENECTADY, NEW YORK, ASSIGNOR TO GENERAL ELECTRIC COMPANY, A CORPORATION OF NEW YORK

APPARATUS FOR PRODUCING SOUND

Application filed March 14, 1929. Serial No. 347,060.

My invention relates to apparatus for producing sound and has for its principal object the provision of an improved sound producing apparatus which is simple and rugged in construction and may be readily operated to convert electrical impulses into sound or vice versa.

In the manufacture of sound producing devices, such as loud speakers for example, it is desirable to simplify the parts so as to facilitate mass production and at the same time to maintain or increase the efficiency of the loud speaker. In accordance with my invention the efficiency of the magnetic type of loud speaker is increased and mass production thereof facilitated by an improved construction in which a coil spool of a resilient metal is provided within which the vibrating armature is fastened to projections from the walls of the spool, which provide the restoring or centering force as well as the fulcrum for the armature.

My invention will be better understood from the following description when considered in connection with the accompanying drawings and its scope will be pointed out in the appended claims.

Referring to the drawings, Fig. 1 illustrates a cross section assembly view of a loud speaker built in accordance with my invention; Figs. 2 and 3 illustrate details thereof, and Figs. 4 and 5 illustrate a modification of the invention.

The sound producing device illustrated in Fig. 1 includes a cone 10 which is driven through a driving rod 11 by an armature 12. The armature 12 is supported by projections 13 and 14 from the walls of a coil spool composed of members 15 and 16 which are preferably made of some resilient non-magnetic and high resistance metal. A coil 17 adapted to receive or generate speech current surrounds the spool, and a permanent magnet 18 provided with pole pieces 19, 20, 21 and 22 produces a magnetic field in which the armature moves.

Fig. 2 illustrates an assembly of the spool and pole pieces illustrated in Fig. 1; and Fig. 3 is an exploded view thereof. The members 15 and 16 are provided with upwardly

and downwardly extending lugs which are bent into locking position when the members are assembled, and which interlock them with each other and with end plates 23 and 24. Space is provided for the pole pieces between the end plates and the spool parts in which the pole pieces are held in place by screws 25. It may be noted in this view that armature 12 is one continuous piece of metal having no grooves cut therein to affect its magnetic reluctance and no separate member is required to support and center it, the lugs 13 and 14 being simply a part of the spool metal.

A modification of my invention is illustrated in Figs. 4 and 5. In this construction the spool consists of one piece of metal 26 which is provided with flanges 27 and 28 for supporting the pole pieces, and a projecting portion 29 to which the armature 12 is fastened. In this modification the projecting portion 29 again provides the restoring force as well as constituting the fulcrum for the armature. This construction is somewhat more simple than the structure illustrated in Figs. 1 to 3.

Sound producing devices built in accordance with my invention have the advantage that the problem of mounting and centering the armature is greatly simplified and the armature is made of a rectangular piece of metal which possesses low magnetic reluctance and tends to increase the operating efficiency of the device.

What I claim as new and desire to secure by Letters Patent of the United States is:—

1. In a sound producing apparatus, a coil spool having a wall provided with an inwardly projecting flexible portion formed from said wall, and an armature arranged to move within said spool and rigidly attached to said portion.

2. In a sound producing apparatus, a coil spool provided with a pair of opposing projecting portions, and an armature arranged to move within said spool and rigidly attached to said portions.

3. In a sound producing device, a hollow sheet metal spool provided with an inwardly projecting portion, an armature arranged to move within said spool and rigidly at-

tached intermediate its ends to said inwardly projecting portion.

4. An integral coil spool including a hollow portion provided with an inwardly projecting support, and flanges bent at an angle with said portion to form the ends of said spool.

5. A speech current device including an integral coil spool including a hollow body portion, a projection within said portion flanges arranged to form the ends of said spool, and an armature mounted on said projection and extending through said body portion.

6. In an acoustic device, a movable armature, a coil spool provided with flanges, and with an inwardly projecting portion adapted to support said armature, and magnetic members arranged to cooperate with said armature and mounted on said flanges.

In witness whereof, I have hereunto set my hand this 13th day of March, 1929.

EMILE C. GUEDON.
